(57) **CLAIM**

We claim the ornamental design for an internal assembly for travel accessory, as shown and described.

DESCRIPTION

FIG. 1 is a front view of an internal assembly for a travel accessory showing our new design.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a top-front-right perspective view thereof.

FIG. 8 is a bottom-front-left perspective view thereof.

FIG. 9 is a bottom-rear-left perspective view thereof; and,
FIG. 10 is a top-rear-right perspective view thereof.

The shade lines show surface contour and not surface ornamentation.

The broken lines depict portions of the internal assembly for a travel accessory that form no part of the claimed design. The dot-dash lines shown in the drawings represent bounds of the claim and form no part of the claimed design.
